UNITED STATES PATENT OFFICE.

HERMAN DRUCK, OF BROOKLYN, NEW YORK.

MECHANICAL TOY BOOK.

Application filed February 8, 1927. Serial No. 166,627.

This invention is a mechanical toy book and, in the preferred embodiment of the invention, it takes the form of a picture book.

The object of the invention is to provide 5 a highly meritorious construction, the mechanical features of which are such as to hold the interest particularly of the uninitiated, by virtue of the somewhat mysterious mode of operation of the device.

10 In its preferred practical form, the invention embodies a plurality of plates preferably of rectangular form and all of the same size. These plates are normally positioned face to face and they are secured together by 15 means of strips, which are, in practice, preferably relatively rigid, but are hingedly secured at their opposite ends to the opposite edges of contiguous plates, so that these strips constitute, in effect, hinge sections.

20 It is highly practical to use three of these hinge sections between each two plates in which event, the center hinge section is secured to one edge of one plate and the opposite edge of the adjacent plate while the 25 other two hinge sections are pivoted to the other edge of the first plate and the opposite edge of the adjacent plate. This construction provides for pivotal movement of each plate on two distinct axes. That is to say 30 on an axis substantially coincident with the lateral edge of each plate, while positively precluding pivotal movement of any particular plate relative to the others on more than one axis at the same time. As a result, 35 it is possible to unfold the plates from their compacted positions in two distinct ways.

When the plates are unfolded in one way, one face of each strip and the corresponding portion of one face of each plate will be 40 closed to view, while the folding of the device the other way will result in disclosing the opposite faces of the respective strips and portions of the opposite sides of the respective plates. It therefore follows that 45

if pictures, letters or symbols are printed on both sides of the strips and plates, the folding of the device in the two ways referred to will result in the exposure of one set of pictures or symbols to the exclusion of the 50 other set and vice versa, depending upon the manner in which the device is unfolded. It is further possible by using, for example four plates, to obtain by the two distinct unfolding operations, fourteen different pictures, letters or symbols, each one substantially coextensive with the size of the plate 55

it being apparent that the outside face of the outside plates will remain unchanged. In this manner, a variety of pictures, numbers, letters or symbols may be exhibited in 60 a thoroughly efficient and practical manner and in a way that is more or less meritorious and calculated to hold the interest.

I have referred particularly to the use of 65 four plates with three strips between each plate. This is one of the forms in which the invention is made. I wish it understood, however, that a greater or lesser number of plates may be used and that the hinging of the consecutive plates together may be ac- 70 complished by two or more hinge strips and that the invention is not limited to the three strips for the purpose specified.

Features of the invention, other than 75 those specified, will be apparent from the hereinafter detailed description and claims, when read in conjunction with the accompanying drawings.

The accompanying drawings illustrate 80 one practical embodiment of the invention, but the construction therein shown is to be understood as illustrative, only, and not as defining the limits of the invention.

Figure 1 is a perspective view of the device 85 of this invention showing one of the plates drawn away from the other plates and in a more or less abnormal position in order to show the manner in which the consecutive plates are respectively secured together by the hinge strips. 90

Figure 2 is a top view of the construction 95 of Figure 1, showing all of the plates drawn apart and in abnormal positions to more clearly show the connections between said plates.

Figure 3 shows the device unfolded and in one position which it is adapted to occupy.

Figure 4 shows the device unfolded and in another position which the parts may occupy; and, 100

Figures 5, 6, 7 and 8 show the different permutations of which the device is susceptible. In these views, Figure 6 corresponds to the showing of Figure 4, and Figure 8 corresponds to the showing of Figure 3, 105 Figures 5 and 7 illustrating the opposite sides of Figures 3 and 4, respectively.

Referring to the drawings, 1, 2, 3 and 4 designate four plates. These plates may be made of any material, but are preferably of 110 cardboard of rectangular shape. Their size is optional, but it is of course desirable

to make them of a size to permit them to be conveniently handled. They are preferably relatively rigid, although they may be slightly flexible without departing from the 5 invention. For the purpose of clear description, the lateral edges of the respective plates are designated 1^a, 1^b, 2^a, 2^b, 3^a, 3^b and 4^a and 4^b, respectively. Between each two plates are positioned a plurality of hinge 10 strips, three being shown for the purpose of illustration. Thus, between the plates 1 and 2 are positioned the strips 5, 6 and 7, and similar strips are positioned between each two additional plates. These strips, which 15 I have termed the hinge strips extend the entire width of the respective plates and are hinged to the opposite edges of said plates. Thus, as shown in Figures 1 and 2, one end of each of the outside strips 5 and 7 is pivoted to the edge 1^a of the plate 1, while the 20 other ends of said strips are pivoted to the opposite edge 2^b of the plate 2. In contradistinction, one end of the strip 6 is pivoted to the edge 1^b of the plate 1, while the other end of said strip is pivoted to the edge 2^a of the plate 2, so that these strips collectively 25 produce a crisscross appearance, as clearly exhibited in Figure 2.

This manner of pivoting the plates together allows of pivotal movement between the respective plates on two distinct axes for each plate. Thus, if the plates are compacted and in substantially face abutting relation, it will be apparent that the plate 30 1 may be pivoted on an axis of the hinge connection between the strips 5 and 6 and said plate. This axis would be positioned at the edge 1^a. Moreover, instead of swinging the plate 1 in the manner stated, the 35 plate 1 is also capable of being swung on the axis of the hinge between the strip 6 and the plate 1, which axes will coincide with the edge 1^b of said plate.

It follows that inasmuch as the several 40 plates are hinged to one another in the manner described, that they are capable of two distinct folding operations, which are shown in Figures 3 and 4. Here the plates are shown as unfolded into substantial alignment. In Figure 3, one manner of unfolding the plates is shown. To bring the plates into the position of this figure, the plates are first compacted and then the device is 45 lifted by grasping it with the thumb and forefinger contiguous to the edge 4^b. The weight of the several plates will cause them to unfold when the device is lifted and this unfolding will be upon the axes of the edges 3^a, 2^b and 1^a.

If the device is now compacted again, and 50 instead of being lifted at the edge 4^b, it is lifted at the edge 4^a, the plates will fall into alignment as shown in Figure 4, said plates pivoting on the axes of the edges 4^b, 3^a and 2^b.

Now, if it be assumed that when the parts are in the position of Figure 3, a letter, number, symbol or picture is printed upon each of the exposed faces and at both sides of the device, and, this printing operation 55 again carried out after the change, as shown in Figure 4, has been made, it will be apparent that fourteen different pictures, letters or symbols will be susceptible of exhibition. In practice, the printing may be 60 done on separate sheets of paper and thereafter properly trimmed and pasted in position or the application of the pictures, numbers, letters or symbols to the parts may be 65 accomplished in any suitable way. I do not 70 limit the invention to any particular manner of production in this respect, but I have referred to the printing upon the parts as 75 illustrative and as clearly showing what the 80 result will be.

I may, in practice, use pictures, numbers, letters or symbols of any character, but, for the purpose of illustration, I have consecutively lettered the parts A to N. Figures 85 5 to 8 show the different permutations which 90 are exhibited by manipulation of the device 95 in the two ways described. Thus, Figure 8 shows the letters as they appear in Figure 3, while Figure 7 shows the letters which appear 100 on the reverse side of the parts, as shown in Figures 3 and 8. Figure 6 shows the letters as they appear in Figure 4, while Figure 5 shows the letters which appear on the reverse side of the parts as illustrated 105 in Figure 4. It will of course be apparent 110 that the letters on the exterior of the cover plates 1 and 2 do not change, and it is for this reason that the A and D appear in both Figures 5 and 7.

It may be here noted that the letters are 115 carried conjointly by the hinge strips and by the plates. That is to say, portions of the letters are formed on the strips and the 120 cooperating portions of the letters directly on the plates. These cooperating portions of the several letters are so arranged that when the folding operations are carried out properly portions of each letter will properly register, so that the aggregate of these 125 portions will give the complete letters. The same arrangement would of course work out with pictures or symbols.

The device while more or less mysterious in its operation, particularly to those who are not skilled in mechanics, is relatively 130 simple in construction and may be economically manufactured. It may be operated with interest by both children and adults.

The foregoing detailed description sets 135 forth the invention in its preferred practical form, but, for the reasons given, I do not restrict the invention to the number of plates employed or to the number of hinge strips entering into the construction. The 140 device is primarily intended for use as a

toy, but the mechanical structure shown, constructed in more durable form and in metals with metallic hinge connections, may be employed in advertising signs and the like. The present invention therefore is to be understood as fully commensurate with the appended claims.

I wish to call particular attention to the relatively great number of pictures which I am able to obtain with a relatively small number of plates. In the showing of the drawings where four plates are used fourteen different pictures result and each of these pictures are substantially of the full size of the respective plates. By increasing the number of plates, the number of pictures which may be obtained will be correspondingly increased. That is to say, when employing five plates, I obtain eighteen pictures, six plates will produce twenty-two pictures, seven plates, twenty-six pictures, etc. In other words, each additional plate added, which, in itself, has but two sides, will result in the addition of four pictures.

Nothing of this sort has ever heretofore been produced.

The term "pictorial representation" as employed in the appended claims is to be construed as sufficiently comprehensive to include a letter or symbol.

Having thus fully described the invention, what I claim as new and desire to secure by Letters Patent is:

1. In a device of the character described, a plurality of plates positioned face to face and between each two of which are interposed at least two hinge strips, one end of one hinge strip being pivotally secured to one edge of one adjacent plate and the other end of said hinge strip being secured to the opposite edge of the contiguous plate, and one end of the other hinge strip being secured to the other edge of the first mentioned plate, and the other end of the latter hinge strip being secured to the opposite edge of the second mentioned plate, and corelative picture elements delineated on corelative surfaces of the strips and plates with each complete picture conjointly carried by a plate and at least one of its associated strips, whereby the picture elements on the plates and strips are mutually cooperative

to form three different complete pictures for each of the end plates and four different complete pictures for each of the intermediate plates.

2. In a device of the character described, a plurality of plates positioned face to face and between each two of which are interposed at least two hinge strips, one end of one hinge strip being pivotally secured to one edge of one adjacent plate, and the other end of said hinge strip being secured to the opposite edge of the contiguous plate, and one end of the other hinge strip being secured to the other edge of the first mentioned plate, and the other end of the latter hinge strip being secured to the opposite edge of the second mentioned plate, the aggregate width of the several hinge strips between any two adjacent plates being substantially equal to the length of the device, and suitable data delineated upon the plates and hinge strips.

3. In a device of the character described, a plurality of plates positioned face to face and between each two of which are interposed at least two hinge strips, one end of one hinge strip being pivotally secured to one edge of one adjacent plate, and the other end of said hinge strip being secured to the opposite edge of the contiguous plate, and one end of the other hinge strip being secured to the other edge of the first mentioned plate, and the other end of the latter hinge strip being secured to the opposite edge of the second mentioned plate, a portion of a pictorial representation delineated on each side of each hinge strip, and the remainders of such pictorial representations delineated on the cooperating plates, and corelative portions of said pictorial representations on the plates and strips being mutually cooperable to form complete pictorial representations, whereby the complete pictorial representations are conjointly carried by the hinge strips and plates collectively with three complete pictorial representations for each of the end plates and four complete pictorial representations for each intermediate plate.

In testimony whereof I have signed the foregoing specification.

HERMAN DRUCK.
